(57) **CLAIM**

The ornamental design for a skin-adhering drug delivery patch, as shown and described.

DESCRIPTION

FIG. 1 is a prospective view of a skin-adhering drug delivery patch showing my new design, wherein the patch has a top half and a bottom half, which are shown coupled together;

FIG. 2 is a rear end view of the skin-adhering drug delivery patch of FIG. 1;

FIG. 3 is a front end view of the skin-adhering drug delivery patch of FIG. 1;

FIG. 4 is a left side elevational view of the skin-adhering drug delivery patch of FIG. 1;

FIG. 5 is a right side elevational view of the skin-adhering drug delivery patch of FIG. 1;

FIG. 6 is a top view of the skin-adhering drug delivery patch of FIG. 1;

FIG. 7 is a bottom view of the skin-adhering drug delivery patch of FIG. 1;

FIG. 8 is a perspective view of the skin-adhering drug delivery patch of FIG. 1 showing the two halves of the skin-adhering drug delivery patch in separated positions, wherein the top half is turned to show the bottom of the top half; and,

FIG. 9 is a perspective view of the skin-adhering drug delivery patch of FIG. 1 showing the two halves of the skin-adhering drug delivery patch in separated positions, exposing the top of the bottom half.
